UNITED STATES PATENT OFFICE

HAROLD H. ELLIOTT, OF GLENCOE, ILLINOIS, ASSIGNOR TO HALSAM PRODUCTS COMPANY, OF CHICAGO, ILLINOIS, A CORPORATION OF ILLINOIS

BOTTLE STOPPER

Application filed February 4, 1928. Serial No. 251,824.

My invention relates to bottle stoppers and particularly to that type of stopper comprising a cork or equivalent part and a head or top of greater diameter secured thereto for improving the appearance of the stopper and for affording means for gripping it for removal from the bottle. It is the object of my invention to provide a new and improved form and arrangement in devices of this type whereby the top or head member may be more securely held in position on the cork.

In the production of devices of this type heretofore, the head or top members in the form of discs of straight grained wood have been waxed and then subjected to very heavy pressure both axially and radially, such pressures serving to close up the grain of the wood as well as to shape the disc. Such heavy pressures in both directions have resulted in so great an increase in the density and resiliency of the whole body of the wood constituting the disc as to discourage the formation of a socket of any considerable depth in the face of the member for receiving the cork in centered position therein, and has made doubly difficult the production of still deeper indentations of a permanent character in the face of the disc inside of the socket. In such cases, it has been found to be almost impossible or at least impractical to impress such auxiliary indentations to such a depth as to expose and to leave exposed unwaxed surfaces of wood at the sides of the indentations to such an extent as to be of any material value for increasing the adhesion of the glue with respect to the head or top.

It is the object of my invention to provide a new construction by which the upper end of the cork is, for a portion or portions of a distance about the cork, in close proximity to unwaxed portions of the side wall of a centering socket so that only a thin film of glue shall be present between the cork and the side wall for insuring firm adhesion, and by which at another portion or other portions the unwaxed side wall of the socket is slightly farther removed from the face of the cork for providing at such points reinforcements of hardened glue in the form of ribs projecting outwardly a very short distance from

the face of the cork and serving as keys for resisting any tendency of the head or top member to turn with respect to the cork. It is one of the objects of my invention to provide such reinforcing ribs or keys of hardened glue in the completed stopper by the provision of suitable irregularities in the side wall of the single depression forming the socket for the cork, such irregularities being readily provided in the side wall of the socket to the desired depth for effectiveness by the use of a correspondingly shaped die, by reason of the fact that such irregularities extend to the full depth of the compression for forming the socket, and by reason of the fact that heavy pressure has not otherwise been applied to the wood axially and radially thereof.

It is another object of my invention to improve devices of this type in sundry details hereinafter pointed out. The preferred means by which I have accomplished my several objects are illustrated in the drawing and are hereinafter specifically described. What I consider as new and desire to cover by Letters Patent is set forth in the claims.

In the drawing,—

Fig. 1 is a bottom face view of my improved top or head member;

Fig. 2 is a vertical cross section taken at line 2—2 of Fig. 1;

Fig. 3 is a bottom view of a completed stopper embodying my invention;

Fig. 4 is a central vertical section through the completed device of Fig. 3; and

Figs. 5, 6, 7 and 8 are views similar to Fig. 1 but showing modified forms of construction.

Referring now to Figs. 1 to 4 inclusive, in which corresponding parts are indicated by the same reference characters,—10 indicates a disc of wood, preferably of straight grain, with the grain running axially, the disc shown being in the form of a short cylinder. In the production of the disc 10, it is prepared originally in the form of a long circular bar of wood, being sawed crosswise by any suitable means to provide the desired preliminary thickness of the disc. The disc is then stained, ordinarily, and is thereafter waxed over its entire surface, after which

it may be polished to a limited extent by a tumbling process, if desired. Following the waxing, the disc is fed between suitable dies to which comparatively heavy pressure is applied serving to compress the wood axially. Such pressure operation serves to close up the grain of the wood, and to increase the strength and resiliency of the disc to a corresponding extent, the action of the dies upon the waxed surface of the wood serving also to give a high polish thereto. The die forming the top face of the head is provided with a suitable design for impressing any desired lettering upon the disc, as is indicated, for example, at 11 in Figs. 2 and 4. For the pressing operation, the disc 10 is inserted into a form which limits the transverse expansion of the wood under pressure, serves to prevent splitting of the wood, and serves also to imprint a design on the edge of the disc if desired. The form is preferably of a size to receive the disc 10 into operative position therein without pressure thereon by either die prior to the final operative pressure between the two dies. The die engaging the bottom face of the disc is provided with an operative portion of reduced size upon which the maximum pressure is applied for forming a depression or socket 12 in the bottom face of the disc in centered position therein. The die forming the socket 12 is pressed directly along the grain of the disc, serving to uncover unwaxed portions of the wood at the side wall portions of the socket, such side wall portions of unwaxed wood being indicated in Fig. 2 by the numeral 13. The die forming the socket 12 is of such shape as to provide a socket of a general circular conformation so as to receive the end of a cork 14 fitted therein with the face portion of the cork in close proximity to the side wall of the socket. The die is of such shape, however, that it provides irregularities in the side wall of the socket with respect to such circular conformation so that the side wall of the socket stands at certain points in slightly spaced relation to the face of the cork. The arrangement is such that when the cork 14 is inserted with a suitable quantity of glue in the socket 12, only a very thin film of glue can be present between the cork and the innermost portions of the unwaxed side wall of the socket, while at intermediate portions considerably greater amounts of glue are retained. Such intermediate greater portions of glue are adapted to harden in the form of ribs or keys which fit in the irregularities of the side wall of the socket serving to prevent any tendency of the disc to turn with respect to the cork.

By reason of the fact that the irregularities in the side wall of the socket extend to the full depth of the socket, the keys or ribs of glue are afforded very strong adhesion

with a comparatively great extent of unwaxed wood at the series of points about the cork, in the form illustrated in Figs. 1 to 4. In the form shown in Fig. 1, the inwardly extending portions of unwaxed wood defining the side wall of the socket are rounded at their inner ends so as to afford a more or less extended bearing or contact between the cork and such parts.

In Figs. 5, 6, 7 and 8, the construction is the same as that above described, except that the center dies for the bottom faces of the discs of such figures are of a slightly different form. In the disc 15 of Fig. 5, the innermost portions of the wall against which the cork contacts are in the form of sharp ribs rather than in the form of rounded ribs as illustrated in Fig. 3. In the disc 16 of Fig. 6, the innermost points are also comparatively sharp, with the irregularities defined by straight angled lines rather than by curved lines. In the disc 17 of Fig. 7, the inwardly extending portions are substantially in the form of square lugs separated by substantially square notches. In the disc 18 of Fig. 8, the arrangement is the same as in Fig. 7, except that only a much smaller number of notches are employed, the greater length of the lugs resulting in such lugs having circular inner faces rather than the square appearing inner faces of the construction shown in Fig. 7. Inasmuch as the operation and effect of the discs as shown in Figs. 5 to 8 are the same as those above described in connection with the disc of Fig. 1, it is believed to be unnecessary to describe these constructions further.

While I prefer to employ the construction as illustrated in the drawing and as above described, it will be understood that I do not limit the invention to the details of the forms shown except so far as claims may be so limited by the prior art.

I claim:—

1. As a new article of manufacture, a disc of wood in which the grain runs axially and having a socket pressed directly along the grain into one face of the disc, such socket being of a generally circular conformation with an enlargement beyond the true circular form defined at at least one end circumferentially of the socket by a comparatively abrupt shoulder.

2. A bottle stopper, comprising in combination a disc of wood having a facing of wax and provided with a socket in one face having an unwaxed side wall, and a cork secured by glue in said socket, said socket conforming generally to the shape of the cork but having an enlargement at at least one point defined at one end by a comparatively abrupt shoulder against which a rib of hardened glue projecting outwardly from the cork bears for resisting any tendency of the disc to turn with respect to the cork.

3. A bottle stopper, comprising in combination a disc of wood having a facing of wax and provided in one face with a single depression of the general conformation of a circle but having a series of irregularities in its side wall, and a cork secured by glue in said depression and fitting closely therein at the innermost portions of the side wall so as to permit the presence of only a thin film of glue between the cork and the wall and provided with a series of outwardly extending ribs of hardened glue extending into the irregular portions of the side wall serving to resist any tendency of the disc to turn with respect to the cork.
